UNITED STATES PATENT OFFICE.

ROBERT HUNTER, OF SPOKANE, WASHINGTON, ASSIGNOR OF ONE-EIGHTH TO HARRY L. WILLIAMS AND ONE-FOURTH TO HENRY W. GREENBERG, BOTH OF SPOKANE, WASHINGTON.

ENGINE.

1,097,548.

Specification of Letters Patent.

Patented May 19, 1914.

Application filed November 17, 1909. Serial No. 528,437.

To all whom it may concern:

Be it known that I, ROBERT HUNTER, a citizen of the United States, and a resident of Spokane, in the county of Spokane and 5 State of Washington, have made certain new and useful Improvements in Engines, of which the following is a specification.

My invention is an improvement in rotary engines, and consists in certain novel constructions, and combinations of parts, hereinafter described and claimed.

The object of the invention is to provide a simply constructed, and easily operated explosion engine of the rotary type, where- 15 in a governor mechanism is provided for controlling the fuel supply, in addition to the usual cam operated inlet valve.

Referring to the drawings forming a part hereof Figure 1 is a side view of the improvement partly in section, Fig. 2 is a plan view, Fig. 3 is a transverse vertical section, Fig. 4 is an end view of the piston, Fig. 5 is a side view of the fly wheel, Fig. 6 is a section on the line 6—6 of Fig. 5, Fig. 25 7 is a section on the line of the wedge, and Fig. 8 is a side and front view respectively of the cams.

The embodiment of the invention shown in the drawings comprises a base 1, which 30 may be of any suitable or desired construction, and the cylinder consisting of a shell 2 and heads 3 and 4 is supported on the base. The shell is provided at its ends with lateral flanges 5, which lap on the base, and are 35 secured thereto by bolts 6.

The rotor comprises a shaft 7, which is journaled in bearings 8 on the base, and a piston 9 secured to the shaft within the cylinder. The piston is provided with di- 40 ametrically opposite wings or vanes 10, each having a front face 11 formed on the arc of a circle eccentric to the shaft, and a rear face 12 which is in a plane which is parallel to the longitudinal axis of the shaft, and at 45 each end of the said face is a rib 13 which moves against the adjacent head of the cylinder.

The free edge of each vane moves against the inner face of the shell, and the 50 ends of the piston and of the vanes move against the heads of the cylinder, an annular groove 14 is provided in the end of each piston concentric with the shaft, and each groove is provided with lateral extensions

15, which extend to the free edges of the 55 vanes.

Packing rings 16 are arranged in each of the grooves, and are supported by springs 17, seated between the rings and the bottoms of the grooves, and each ring is pro- 60 vided with extensions 18 fitting within the extensions of the grooves. The free edge of each vane is also grooved as at 19, and packings 20 are arranged in the grooves.

An explosion chamber 24 is arranged at 65 the top of the cylinder, and communicates with the cylinder by a port 24^a, and at one end of the explosion chamber an abutment 22^a is movable radially of the shaft 7, and toward and from the periphery of the rotor. 70 The abutment is movable in the chamber 21, and the said chamber is closed by a cap 22, secured in place by cap screws 23. It will be noticed that the periphery of the rotor is eccentric to the shaft so that when 75 the rotor moves in the direction of the arrow shown in Fig. 3, the abutment will be lifted to permit the vane to pass thereby.

The sparking device 25 is arranged in the explosion chamber, at its outlet into the cylinder. The sparking device comprises a fixed electrode 26, and a movable electrode 27, arranged on the end of a shaft 28. The shaft is journaled in bearing 29 on the cylinder, and outer end thereof is provided with 85 a crank arm 30.

A cam 31 is secured to the shaft adjacent to the cylinder, and a lever 32 is pivoted by one end to the cylinder as at 33, the opposite end engaging the cam. A link 34 connects 90 the crank arm 30 with the lever 32, and a spring 35 presses the lever against the cam.

It will be evident that when the shaft 7 rotates, the movable electrode will engage the fixed electrode at regular intervals, and 95 the usual jump coil and batteries or other source of electrical energy is arranged in circuit with the electrodes thereby to produce a spark when the electrode disengage. Such construction however forms no part of 100 the invention, and it is not thought necessary to illustrate the same.

The explosive mixture is conducted to the explosion chamber by a pipe 36, which delivers at the outer end of the chamber, and 105 the admission of the mixture is controlled by a valve 37, which is usually held closed, and is opened at regular intervals by an arm

39, on a shaft 40, journaled in bearings 41 on the cylinder.

The outer end of the shaft 40 is provided with the arm 39, which is connected by a link 43, with a lever 44 pivoted as at 45 on the adjacent cylinder head. The free end of the lever is normally pressed into engagement with a cam 46 secured to the shaft, by means of a spring 47. As the shaft 7 rotates the cam 46 will oscillate this shaft 40 to open the valve at regular intervals, to admit a supply of mixture. The cams 31 and 46 are arranged to operate in sequence, so that the charge is ignited at the proper time. The supply of explosive mixture is further regulated by a valve 49, arranged in a casing 50 interposed in the supply pipe. The valve is of the rotary type, and is provided with a stem 51 extending outside of the valve casing, and provided with a crank arm 52.

A lever 53 is pivoted by its center to a bracket 54 on the base, and one end of the lever is connected by a link 55 with the crank arm 52. The other end is provided with a fork 53^a, having set screws 54^a threaded therethrough, and the set screws engage openings in blocks 55^a, which move in an annular groove 56 in a collar 57 slidable longitudinally of the shaft 7.

The collar is provided on its outer face with radial grooves 58, which register with radial grooves 59, in the hub 60, of a fly wheel 61 secured to the shaft 7. Levers 62 are pivoted on spokes 63 of the fly wheel, the outer end of each of said levers having a weight 64.

Wedges 65 are movable in the registering radial grooves, and each wedge is provided in its larger and outer end with an opening 66, through which passes the opposite end of one of the levers. The levers are two in number, and are arranged at diametrically opposite points, and the weighted ends 45 are adapted to be thrown outward when the fly wheel rotates, by centrifugal force. When the weighted ends move outward, the wedges are moved radially inward, and the collar 57 is pressed away from the fly wheel, 50 against the resistance of the springs 70, which normally press it toward the said fly wheel. When the collar moves away from the fly wheel, the lever 53 is rocked, and through the link 55 the valve 49 is rotated.

The arrangement of the valve is such that when the engine is running at normal speed, the valve will be about one half opened. When the speed of the engine exceeds this speed, the governor mechanism just described operates to partially close the valve, and when it falls below the predetermined speed the valve is opened wider, to admit a greater supply of mixture.

In operation the engine is started in any suitable manner, and as the shaft 7 rotates,

charges of explosive mixture will be drawn into the explosion chamber, ignited and passed into the cylinder. The force of the explosion will be exerted on the wing or vane, and on the abutment 22^a, and since 70 the abutment is fixed, the piston will rotate. Just before the other vane passes the inlet, the first vane passes the exhaust port 68, and the products of combustion pass out of the cylinder. The second vane then passes 75 the inlet and receives the force of the explosion of the next charge. The cams 31 and 46 are arranged to operate their respective mechanisms twice during each rotation of the shaft 7.

Springs 69 are arranged between the outer ends of the levers 62 and the spokes, and normally draw the weighted ends of the levers inwardly, and the wedges outwardly, and other springs 70, arranged between the 85 collar 57 and the fly wheel assist in this action.

The casing of the cylinder is water-jacketed, as shown at 71, and is supplied with a cooling fluid by pipes 72, and the piston is 90 hollow as shown at 73 for receiving a cooling fluid. The cooling mixture may be supplied to the piston in any suitable manner. Such mechanism forming, however, no part of the invention, has not been shown nor described. The extensions 18 of the packing rings are also shown as sectional, Fig. 4.

I claim:

1. An engine of the character specified, comprising a base, a cylinder supported on the base, a shaft journaled in the cylinder, a piston on the shaft, said piston having diametrically opposite wings or vanes, each of said vanes having its operative face in a plane passing through the longitudinal axis of the shaft, said faces being recessed and the opposite face being inclined, said cylinder having an inlet port and an exhaust port, an explosion chamber communicating with the inlet port, a sparking device in the explosion chamber, a fuel supply pipe for the said chamber, an inlet valve for the supply pipe, a plurality of cams on the shaft, a connection between one of the cams and the sparking device for operating the same, a connection between the other cam and the inlet valve for operating said valve, a rotating valve in the supply pipe, a pivoted lever having one end connected with the valve, a collar slidable on the shaft to which the other end of the lever is connected, and a governor operated by the shaft for moving the collar.

2. An engine of the character specified comprising a base, a cylinder supported on the base, a shaft journaled in the cylinder, a piston on the shaft, said piston having diametrically opposite wings or vanes, said cylinder having an inlet port and an exhaust port, an explosion chamber communicating 120

- with the inlet port, a sparking device in the explosion chamber, a fuel supply pipe for the said chamber, an inlet valve for the supply pipe, a plurality of cams on the shaft, 5 a connection between one of the cams and the sparking device for operating the same, a connection between the other cam and the inlet valve for operating said valve, a rotating valve in the supply pipe, a pivoted lever having one end connected with the valve, a collar slideable on the shaft to which the other end of the lever is connected, and 10 a governor operated by the shaft for moving the collar.
- 15 3. An engine of the character specified,

comprising a cylinder, a shaft journaled therein, a piston provided with vanes on the shaft, means for admitting a charge to the cylinder, an igniting device, means operated by the rotation of the shaft for igniting the charge admitting means and the igniting device, a governor operated by the shaft, and means controlled by the governor for regulating the quantity of the charge admitted. 20
